PLECTRUM HOLDER

Christer Olof Gardsby, Svalbogatan 3,
Malmo, Sweden

Filed Dec. 6, 1967, Ser. No. 9,658

Term of patent 14 years

Int. Cl. D17—99

U.S. Cl. D56—1

FIG. 1

FIG. 2

FIG. 3

FIG. 4

FIGURE 1 is a front elevational view of a plectrum holder showing my new design;

FIGURE 2 is a left side elevational view;

FIGURE 3 is a right side elevational view; and

FIGURE 4 is a rear elevational view thereof.

I claim:

The ornamental design for a plectrum holder, substantially as shown.
